UNITED STATES PATENT OFFICE.

JESSEE HUESTICE MAXWELL, OF BARBOURSVILLE, WEST VIRGINIA.

WRENCH.

1,152,195.

Specification of Letters Patent. Patented Aug. 31, 1915.

Application filed December 15, 1914. Serial No. 877,406.

To all whom it may concern:

Be it known that I, JESSEE H. MAXWELL, a citizen of the United States, residing at Barboursville, in the county of Cabell and State of West Virginia, have invented new and useful Improvements in Wrenches, of which the following is a specification.

The present invention relates to improvements in wrenches which are primarily adapted to removing nipples from pipe connections, such as valves, T's, L couplings, etc., where short nipples are used, the device working upon the inside of a nipple so as not to destroy the thread thereof, and one of the objects of the invention is to construct a wrench of this class which shall embody the desirable features of simplicity, cheapness in construction and effectiveness in operation.

Another object of the invention is to construct a wrench for the purpose mentioned which shall include a round or cone-shaped head that is provided with longitudinal teeth for a portion of its circumference, but which is also provided upon its smooth surface with an eccentrically arranged segment located in a slot in the wrench and having its outer periphery provided with longitudinal teeth, whereby when the wrench is rotated in one direction, the segment will be moved outwardly of the periphery of the wrench to be brought into engagement with the article to be operated upon.

A further object of the invention is to provide a wrench of this class with a solid head having an eccentrically arranged pocket upon its face, the said pocket being formed with a transverse slot for the reception of a web arranged upon the inner face of an eccentric member which is normally deposited in the open face of the wrench, a pin passing through an elongated slot in the web of the eccentric member whereby the said member may be readily removed from the head.

With the above and other objects in view, the improvement resides in the construction, combination and arrangement of parts set forth in the following specification and falling within the scope of the appended claim.

In the drawing: Figure 1 is a perspective view of a head of a wrench constructed in accordance with the present invention, Fig. 2 is a transverse sectional view approximately on the line 2-2 of Fig. 3, Fig. 3

is a longitudinal section taken on the line 3-3 of Fig. 2, Fig. 4 is a view looking toward the face of the head provided with the recess and depression for the eccentric member, and Fig. 5 is a perspective view looking toward the inner face of the eccentric member.

Referring to the drawing in detail, the numeral 1 designates the head for the wrench, the same being round in cross section, and having one of its ends formed with a projecting, preferably squared stud 2, which receives the handle for the head. The head 1 is provided upon one of its faces with longitudinally extending intersecting ribs and depressions forming teeth 3, and the face or portion of the head not formed with the teeth is provided with a transverse depression, the end walls of which being parallel with the opposite sides of the head, and formed within the said depression to one side of its straight inner wall is a round enlargement or bearing surface 4. The round surface 4 is centrally provided with a transverse slot or depression 5, the opposite walls of which being parallel and the end walls being arranged flush with the end wall of the depression. Passing through the opposite parallel walls provided by the slot 5 as well as through the round bearing surface and through the opposite ends of the head is a circular opening or orifice 6, the walls of which being tapered to receive a tapered pin 7, and the head or enlarged end of said pin extends a suitable distance beyond the wrench. This pin 7 is adapted to be received within an elongated slot 8 provided in a centrally arranged web member 9 formed upon the underface of a segmental member 10. Both the inner and outer faces of the segment are rounded, and the said outer face is provided with teeth 11. The member 10 is of a greater thickness at one of its ends than at the other, so that the same may be snugly received within the recess or pocket provided in one of the faces of the wrench and lie flush with the periphery of the said head. It will be also noted that when the teeth 11 contact with the inner surface of a pipe, nipple or the like, and the head is rotated in one direction, the enlarged end will be forced by the round bearing surface 4 beyond the periphery of the head so that the same will firmly engage with said pipe or nipple. It is to be understood that the teeth 11 of the seg-

mental member 10 engage with the inner surface of the article to be operated on with sufficient friction to cause the same to rotate within the pocket provided by the open face 5 of the wrench, and it is to be understood that the rounded or bearing surface may be arranged to either side of the said pocket in accordance with the direction with which the segmental member is adapted to travel, 10 as for instance, the head may be adapted to operate in either a left or right hand direction.

From the above description, taken in connection with the accompanying drawing, 15 the simplicity of the device, as well as the advantages thereof will, it is thought, be perfectly apparent to those skilled in the art to which such invention appertains without further detail description.

20 Having thus described the invention, what I claim is:

In a wrench for the purpose set forth, a 25 round head having peripheral teeth for a portion of its circumference, said head opposite its teeth being formed with a depre-

sion providing a pocket, a round bearing surface within the pocket and arranged adjacent one of the ends of the pocket, said bearing surface having a transverse slot, a segmental member arranged within the 30 pocket and partially filling the same, said member having outer peripheral teeth and a central web which is arranged within the slot in the bearing surface, the said segmental member having one of its ends of a 35 greater thickness than the second end whereby when the same is rotated a portion of its teeth will be projected beyond the periphery of the head, and a pin passing through 40 the head and through an elongated opening in the web of the segmental member for removably securing the said member upon the head.

In testimony whereof I affix my signature in presence of two witnesses.

JESSEE HUESTICE MAXWELL.
